UNITED STATES PATENT OFFICE.

WILLIAM H. COLE, OF PHILADELPHIA, PENNSYLVANIA.

CONSTRUCTION OF BOATS.

No. 927,640.

Specification of Letters Patent.

Patented July 13, 1909.

Application filed March 24, 1908. Serial No. 422,953.

To all whom it may concern:

Be it known that I, WILLIAM H. COLE, of Philadelphia, county of Philadelphia, and State of Pennsylvania, have invented a new and useful Improvement in the Construction of Boats, of which the following is a specification.

My invention relates to the manufacture of boats, especially small pleasure and life 10 boats.

The invention consists of a cork composition, consisting of granular cork and oxidized linseed oil, reinforced with a perforated steel sheet, as a material suitable for boat 15 construction.

I propose to stamp steel sheets into forms best adapted to the several kinds of boats, then perforate the said steel sheets with a semi-circular perforation forming lips on 20 both sides of the steel sheet, and cover said steel sheet on both sides with a suitable thickness of said cork composition, and subject the whole structure to a pressure of high degree with dies made of concrete or other 25 suitable material, making a complete form for boats. By this arrangement I get a structure that is especially adapted for boats of the kind herein mentioned, inasmuch as the cork material will make the boat buoyant, 30 and by submitting the cork composition to the said pressure I get a resilient material which when reinforced with the sheet of steel makes a strong serviceable and buoyant boat that can be manufactured cheaply and be 35 used with a degree of safety and satisfaction not found in boats of other construction.

I do not claim that the use of cork in connection with boat construction is a new idea, but what I do claim as being a new idea and 40 original in my invention is the combination of the cork material with the steel reinforcement, and the arrangement of the steel reinforcement with this particular kind of a semi-circular perforation or lip extending 45 from both sides of the steel sheet which is pressed into the cork composition and when subjected to a pressure makes the whole structure a solid and substantial mass especially desirable for boat construction.

Figure 1—is a sectional view. Fig. 2—is a 50 perspective view partly in section.

Similar letters refer to similar parts throughout both drawings.

In Fig. 1: A—represents the granular cork composition held to steel reinforcement, B— 55 by projecting perforations or steel lips.

In Fig. 2: A—represents the cork composition on both sides of the steel reinforcement, B— held securely in place by projecting steel 60 lips.

The steel sheets are to be pressed into such forms as will be suitable for the several kinds of boats and the semi-circular perforations forming the lips on both sides of the steel sheet will be made with dies and forced out 65 from the surface of steel sheet for the purpose of holding the cork composition to the steel reinforcement making a structure desirable for boats as above described.

Having thus described my invention what 70 I claim as new and desire to secure by Letters Patent is—

1. A boat comprising an inner and outer lining of granular cork composition with an intermediate metallic reinforcement, said reinforcement provided with fastening lips projecting into said cork linings. 75

2. A boat structure consisting of perforated steel sheet with an inner and outer lining of granular cork composition subjected 80 to a pressure of 6000 pounds to the square inch.

3. A boat structure consisting of a perforated steel sheet with an outer and inner lining of granular cork composition, the outer 85 lining being of the proportion of half of that of the inner lining.

4. A steel reinforcement for boat construction with semi-circular projecting lips, so arranged that projections point alternately up 90 toward the gunwales and down toward the keel of the boat.

5. A perforated steel boat structure with an outer and inner lining of granular cork composition made water tight by subjection 95 to great pressure.

In testimony whereof I affix my signature in presence of two witnesses.

WILLIAM H. COLE.
